COMBINED ELECTRIC MOTOR AND FRAME

Yasuhiro Ohishi, 26-34, 5-chome, Nakano, Nakano-ku,
Tokyo, Japan

Filed July 17, 1972, Ser. No. 272,621

Term of patent 14 years

Int. Cl. D13—01

U.S. Cl. D26—5 A

FIG. 1

FIG. 2

FIG. 3

FIG. 4

FIG. 5

FIG. 6

FIG. 1 is a front elevational view of a combined electric motor and frame showing my new design,

FIG. 2 is a rear elevational view thereof,

FIG. 3 is a top plan view thereof,

FIG. 4 is a bottom plan view thereof,

FIG. 5 is a right side elevational view, which is the same as the left side elevational view thereof, and

FIG. 6 is a perspective view thereof.

I claim:

The ornamental design for a combined electric motor and frame, substantially as shown.
